DESIGN FOR A LIP BRUSH

Walton B. Crane, Beverly Hills, Calif., assignor to
E. Manuel Stolaroff, Los Angeles, Calif.

Application February 13, 1946, Serial No. 126,532

Term of patent 14 years

(Cl. D86—10)

To all whom it may concern:

Be it known that I, Walton B. Crane, a citizen of the United States of America, residing in the city of Beverly Hills, in the county of Los Angeles, State of California, have invented a new, original, and ornamental Design for a Lip Brush, of which the following is a specification, reference being had to the accompanying drawing, forming a part thereof.

Fig. 1 is a perspective view of one side of a lip brush showing my new design;

Fig. 2 is a perspective view showing the other side thereof;

Fig. 3 is a perspective view of the lip brush in partially open position;

Fig. 4 is a perspective view of one side of the lip brush in open position;

Fig. 5 is a perspective view of the other side of the lip brush in open position; and

Fig. 6 is a front end elevational view of the lip brush.

I claim:

The ornamental design for a lip brush, substantially as shown.

WALTON B. CRANE.
